PLASTIC HYPODERMIC SYRINGE

Harry W. Nelson, Arlington, N. J.

Application October 15, 1948, Serial No. 54,600

4 Claims. (Cl. 128—218)

1

The subject of this invention is a novel and valuable hypodermic syringe.

The present invention involves my discovery, verified by actual and repeated tests, that a hypodermic syringe having its cylinder or barrel and also its piston or plunger made of the plastic known as nylon has unique advantages.

As is well-known a hypodermic syringe is an instrumentality which is essential to the surgeon and physician, and one of paramount importance in saving life, in defeating pain, in instantaneously effecting anaesthesia in operative emergencies, and, as for injecting streptomycin and the like, in not only hastening the healing of operative wounds but also for preventing fatalities following serious operations.

A hypodermic syringe, it will be appreciated, should have no brittle and frangible parts, and it also should be capable of sterilization prior to its actual use. Glass syringes have one long-recognized disadvantage. They are fragile and easily broken, making them wholly unsafe for use after breakage or if cracked; and ordinarily dangerous to use, because of the chance of breaking, cracking or chipping during use. Their essential fragility, the lesser of the two just mentioned defects, is, nevertheless, a serious one from the standpoint of expense; or if the barrel alone breaks, the piston or plunger, usually made to fit a particular barrel, is rendered useless; and if the plunger breaks, the barrel is rendered useless. The idea of making these parts of a material other than glass has been an intriguing one; but such an idea has long been considered abortive, because of the prime necessity that the syringe must be made of some material capable of being boiled for sterilization and otherwise sterilizable. True, it has been found that some plastics can be sterilized by immersion in alcohol, but this is inadequate for many uses required of a hypodermic syringe.

I have discovered, as already stated, that all these difficulties are fully overcome if the syringe parts having to be sterilized are made of nylon. As is known, this material is non-brittle; and what I have demonstrated is that an article made of nylon can be sterilized by the standard procedures of boiling, autoclave steaming and chemical sterilization.

By the present invention there is provided a hypodermic syringe in which all the parts thereof requiring sterilization are made wholly of nylon. A simple form of hypodermic syringe is one comprising merely two parts; a cylinder or barrel terminating at its discharge-orifice end in a hollow nozzle, and a piston or plunger; in an arrangement such that, the fluid substance to be injected into the body of a patient may be drawn into the barrel by an aspirating stroke of the plunger and subsequently injected by forcibly advancing the plunger against the body of liquid in the barrel. Merely by way of illustration, and not in any way to limit the applicability of the invention to hypodermic

2

syringes, an embodiment of the invention is herein illustrated and described of the two-part kind just described.

A feature of the present invention, further, is a shaping of the nylon plunger at its inner or working end so that the same there incorporates a special annular flare, or skirt, the tip or working end of which may, if desired, but not necessarily, be a few thousandths of an inch larger in diameter than the internal diameter of the cylindrical main interior of the barrel. Such a flare, with both the barrel and the plunger made of nylon, gives a result long sought in the art, which is to obtain the effect of a positive seal, making the syringe absolutely leak-proof under the pressures created in use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

25 Fig. 1 shows the embodiment above mentioned, in side elevation, with the plunger sent all the way into the barrel, and with the latter partially broken away and partially in section; this view being drawn to about full scale in the case of say a two c. c. capacity syringe.

Fig. 2 is an end elevation, looking toward the left in Fig. 1.

Fig. 3 shows the plunger, drawn to about twice full scale, and also, in axial section, a portion of the barrel intermediate its ends.

Fig. 4 is, on a scale much enlarged over that of Fig. 3, a fragmentary axial section taken through the plunger at its working end; this view being taken on the line 4—4 of Fig. 3.

40 Referring to the drawing more in detail, the barrel illustrated is as a whole marked 10. Said barrel is shown as a single piece of nylon, which may be molded to the desired shape all over, and which includes a main plunger receiving portion 11 cylindrical inside and outside, a finger-hold flange 12 elongated laterally of said portion 11 and at the fully open or rear end of the barrel, and a nozzle portion 14. Said nozzle of course is hollow from end to end, as indicated at 15, with this channel through the nozzle communicating at its inner end with the interior of the main portion 11 of the barrel at its inner end. The free extremity of the nozzle 14 may be blunt as shown, or rounded, or converged to a fine needle point; or, if desired, the outer end portion of the nozzle may be kept substantially as shown or otherwise contoured and externally threaded for attachment thereto of a removable and replaceable fine hollow needle of metal or the like.

I have found that a somewhat grayish milky white nylon gives excellent results, as having all the essential attributes already mentioned, and also the advantage that it is sufficiently

transpicuous to permit the liquid therein to be observed through the side wall of the main portion 11 of the barrel when that wall is made rather thin. The thinness of this wall is, furthermore, now deemed of some importance, because it is apparently of considerable effectiveness in coacting resiliently yieldingly with a special formation at the inner or working end of the plunger to be explained in a moment and including the flare aforesaid. But by no means is the invention to be limited to a somewhat grayish milky nylon or any other colored or tinted nylon, as a transparent nylon may well serve or any other plastic having characteristics of nylon as to its ability to withstand repeated sterilization, without distortion, by conventional procedures including those involving substantial temperatures and having the desired degree of resiliency and elasticity.

Referring to the piston or plunger, this, which is as a whole marked 16, is exteriorly cylindrical, and may be of a diameter over the major part of its length either substantially the same as the interior diameter of the main barrel portion 11 or suitably less than the interior of said main barrel portion so as to have any suitable or desired clearance therefrom. Such major part of the length of the plunger is actually the plunger proper 17, and the plunger comprises said portion 17 and, at the outer end of the plunger, a centralized annular flange, preferably of less diameter than the maximum facewise dimension of the finger-hold flange 12 on the barrel 10, for providing an integral thumb-thrust button 18.

At the working end of the plunger is the aforesaid slight special flare or skirt, as may be noted in Fig. 3, but which is clearly shown in Fig. 4 and there marked 19. There is some lateral flexibility or elasticity of said flare due to the nature of the nylon, with the parts relatively dimensioned as indicated; and for coacting with this flexibility an additionally advantageous feature may be the flexibility of the side wall of the main barrel portion 11 due to its desirable extent of exceptional thinness, as a thickness for said wall of the order of about one-twelfth of the external diameter of the said main barrel portion 11 preferably is provided.

An additional advantageous feature, to constitute the flare or skirt 19 in a manner to augment its sealing efficacy, is a cavitation such as indicated at 20 at the working end of the plunger, to permit the annular wall of the flare or skirt 19 to be of minute thinness immediately adjacent to its circularly extended crest and at the same time to make this crest self-sustaining by a gradual increase in the thickness of said flare or skirt in a direction away from its crest, as indicated at 21. In other words, because of the thin or relatively sharp, knife-like free edge or crest of the flare or skirt 19, said edge or crest has tight-sealing substantially line contact with the inner surface of the barrel 10, particularly since the flare or skirt 19 is more or less elastic and is more or less expanded under the pressure developed in the barrel 10 by movement of the plunger 16 against a body of liquid contained in said barrel during normal use of the syringe. For maximum efficiency of the cavitation 20 in the regard just noted, the cavitation is desirably made so that all cross-sections taken thereof axially of the plunger 16 will define substantially the shape shown in Figs. 3 and 4. It will be observed that the surface of the cavi-

tation 20 presented by plunger material is entirely or substantially in correspondence with the convex surface of a segment of a sphere.

While I have illustrated and described the preferred embodiment of my invention, it is to be understood that I do not limit myself to the precise construction herein disclosed and the right is reserved to all changes and modifications coming within the scope of the invention 10 as defined in the appended claims.

Having thus described my invention, what I claim as new, and desire to secure by United States Letters Patent is:

1. A hypodermic syringe comprising a barrel, 15 a plunger slidable in said barrel, and an annular outwardly and forwardly flaring skirt integral with said plunger adjacent the distal end thereof, said skirt having substantially annular line contact at its inner or free edge with the inner surface of said barrel and being spaced throughout the remainder of its length from the inner surface of said barrel, said skirt being sufficiently elastic at its inner or free end portion to be urged radially outwardly into tight sealing annular 25 substantially line contact with the inner surface of said barrel under the pressure developed by movement of said plunger in said barrel against a body of liquid contained therein in the normal use of the syringe and to yield radially inwardly 30 only on the entry of said plunger into said barrel.
2. A hypodermic syringe as set forth in claim 1 in which the skirt tapers in cross section toward its inner or free end to an extent sufficient to ensure elasticity only at said free end.
3. A hypodermic syringe plunger for use with a hypodermic syringe barrel of predetermined inside diameter, said plunger including a main part and an integral annular outwardly and forwardly flaring skirt adjacent its distal end, 40 said skirt tapering in thickness towards its inner or free end, said end of said skirt being dimensioned to establish a substantially annular line contact seal with the barrel when inserted therein and being sufficiently elastic to be urged 45 outwardly under the pressure developed by movement of said plunger into said barrel against a body of liquid contained therein, as in the normal use of a hypodermic syringe, without appreciably increasing the area of contact between said skirt 50 and said plunger and to yield radially inwardly only when inserted into said barrel.
4. The hypodermic syringe plunger of claim 3 in which the main part and the skirt thereof are of nylon and the skirt has an unbroken 55 surface skin.
